UNITED STATES PATENT OFFICE.

ADAM KWIKKEL, OF BOYDEN, IOWA.

HORSESHOE.

No. 861,130.

Specification of Letters Patent.

Patented July 23, 1907.

Application filed May 8, 1907. Serial No. 372,467.

To all whom it may concern:

Be it known that I, ADAM KWIKKEL, a citizen of the United States, and a resident of Boyden, in the county of Sioux and State of Iowa, have invented an Improved Horseshoe, of which the following is a specification.

My invention is an improvement in that class of horse shoes which are provided with detachable calks. I have devised an improved construction whereby the calks are held securely while in use, but may be easily and quickly detached when required.

The details of construction, arrangement, and combination of parts are as hereinafter described, and illustrated in the accompanying drawings, in which

15 Figure 1 is a perspective view of a horse-shoe constructed and provided with calks according to my invention. Fig. 2 is a section on the line 2—2 of Fig. 1. Fig. 3 is a section on the line 3—3 of Fig. 1. Fig. 4 is an inverted plan view of a heel calk. Fig. 5 is a 20 similar view showing a modification. Fig. 6 is an inverted plan view of a toe calk. Fig. 7 is a plan view of one of the heel portions of the shoe, the calk being detached. Fig. 8 is an end perspective of a calk.

As shown in Figs. 1, 2, 3, a horse-shoe of the usual 25 form is provided with bosses, or raised portions 1, 2, at the toe and heel, respectively. In each of such bosses there is formed, see Fig. 7, a groove 4 which is dove-tailed in cross-section and tapered from one end to the other. The shanks of the toe and heel calks 30 are correspondingly constructed; that is to say, the shanks 5 are dove-tail shape in cross-section and tapered from end to end, and adapted to slide into the sockets 4.

As shown in Figs. 4, 6 and 8, the shanks of the heel 35 and toe calks are slotted crosswise and lengthwise, as at 6, 6^b. Figs. 1 and 8, thus forming practically two jaws or wings. In place of the groove 6 extending the entire length of the calks, it may extend but a short distance as indicated at 6^b in Fig. 5.

40 When the calk is inserted in place, as indicated in Figs. 1, 2, 3, considerable force is required in order to force it to the required position, and this may be conveniently applied by means of a hammer or other tool. When so inserted the taper of the calks and sockets

prevents the former moving in one direction, and to 45 prevent them sliding backward, or in the other direction and thus becoming loosened or detached the jaws or wings formed at the smaller ends of the calks are spread by means of a chisel, or other tapered tool, inserted in the outer end of the slit or groove 6 or 6^b— 50 see dotted lines Figs. 5 and 6. The flexibility of the metal permits this operation, and the form or flare thus imparted is retained and prevents the calk becoming accidentally detached. The side of the groove or socket 4 in the shoe proper are cut away slightly at 55 the smaller end, to form a space, permitting the free lateral expansion of the calk shanks. The hold thus given to the calks is not, however, such as to prevent their being driven out of the shanks by means of a hammer and punch or other tool which may be used 60 for the purpose. Thus, it is at all times practicable to replace a broken or worn-out calk by a new one.

In Fig. 1, I show a toe calk having tapered points 8 which are connected by a wedge-shape bar 9 whose height is about one-half that of the calk proper. By 65 such construction and arrangement I provide the toe calk with an additional part for holding the shoe on the ground and also strengthen or support the points 8.

I claim—

1. A horse-shoe provided with dove-tail and tapered 70 sockets whose smaller ends are enlarged laterally and calks having corresponding dove-tail and tapered shanks adapted to said sockets so that when driven they wedge therein, the shanks having a lengthwise slit extending inward from the smaller end, thus forming expandible jaws, 75 as and for the purpose specified.

2. A horse-shoe proper having a dovetail and tapered socket, a calk having a corresponding shank adapted to wedge therein, and having its smaller end provided with vertical and transverse slits thus forming flexible jaws 80 which are spread laterally and engage the shoe, as shown and described.

3. A horse-shoe having a dovetail and tapered socket, a calk having a shank of corresponding shape and size and provided at its smaller end with a slit dividing it into two 85 jaws or wings which are expanded laterally, as shown and described.

ADAM KWIKKEL.
